CLAIM

The ornamental design for a patterned sheet material as shown and described.

DESCRIPTION

1. Patterned sheet material

- 1.1 : Perspective
- 1.2 : Front
- 1.3 : Back
- 1.4 : Right
- 1.5 : Left
- 1.6 : Top
- 1.7 : Bottom

The broken lines in the reproductions depict portions of the patterned sheet material that form no part of the claimed design.

1 Claim, 7 Drawing Sheets
